(57) **CLAIM**

The ornamental design for jewelry, as shown and described.

DESCRIPTION

FIG. 1 is a rear, top, and right side exploded perspective view of jewelry;

FIG. 2 is a front, top, and right side perspective view thereof in a closed position;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a bottom plan view of a top part thereof; and,

FIG. 10 is a top plan view of a bottom part thereof.

The broken lines in the drawings depict environmental subject matter only and form no part of the claimed design.
